IMPROVEMENT IN CASES

Joseph V. Miller, Auburn, and Robert C. Reed, Sturbridge, Mass., assignors to American Optical Company, Southbridge, Mass., a voluntary association of Massachusetts

Application December 6, 1951, Serial No. 260,142

6 Claims. (Cl. 206—6)

1

This invention relates to improvements in cases and has particular reference to the provision of a simple, efficient and inexpensive spectacle case and method of making same.

It is one of the principal objects of this invention to provide a spectacle case comprising a main pouch portion having a separate cover portion attached thereto by hinge means constructed and arranged in such manner as to continually urge the cover in the direction of closed relation with the pouch portion and to yieldably permit the cover to be opened to a position whereby spectacles may be easily inserted in or removed from the pouch portion, and to provide a novel and inexpensive method of making same.

Another object is to provide a spectacle case of the above character wherein the means for connecting the cover portion to the pouch portion is inherently resilient to permit said cover portion to be manually moved by a hinging action to an open position with respect to said pouch portion and to function automatically to urge the cover portion into closed relation with the pouch portion when said cover portion is released.

Another object is to provide a case of the above character wherein the hinge member connecting the cover portion to the pouch portion embodies an elongated member formed of rubber or similar resilient material having enlarged spaced portions whereby when said member is inserted through the aligned openings in said pouch and cover portions to hingedly connect said portions, the enlarged portions will thereafter prevent retraction of the member from said aligned openings.

Other objects and advantages of the invention will become apparent from the following description taken in connection with the accompanying drawing, in which:

Fig. 1 is a front elevational view of a spectacle case embodying the invention;

Fig. 2 is a top plan view of the case shown in Fig. 1;

Fig. 3 is a perspective view of a hinge member of the preferred type;

Fig. 4 is a vertical sectional view taken substantially on line 4—4 of Fig. 2 showing the cover in closed position;

Fig. 5 is a view similar to Fig. 4 showing the cover in open position;

Fig. 6 is a fragmentary sectional view of a case illustrating a modified form of hinge;

Fig. 7 is a vertical fragmentary sectional view taken on line 7—7 of Fig. 6 showing the cover in closed position; and

2

Fig. 8 is a sectional view similar to Fig. 7 showing the cover in open position.

Referring more particularly to the drawing wherein like characters of reference designate like parts throughout the several views, the device embodying the invention comprises a one-piece pouch 10 of a size and shape to receive a pair of spectacles and a cover 15. The pouch 10 is preferably provided with integral pocket portions 11 and 12 having an upwardly curving portion 13 in the lower surface thereof which is adapted to extend into the space between the respective lens portions of a pair of spectacles when inserted in the pouch 10. The upper side of the pouch 10 is open and the peripheral edge 14 thereof is preferably substantially flat throughout.

A cover 15 is adapted to be mounted over the upper side of the pouch 10 and embodies a substantially flat top portion 16 having depending integral sides 17 which are adapted to fit over the upper peripheral edge 14 of the pouch 10 as shown in Figs. 1 and 4.

The entire case is preferably formed of a semi-rigid plastic material, but may, if desired, be formed of metal, or the pouch 10 and cover 15 may each be formed of pressed paper, plastics or other desirable materials.

The preferred means for connecting the cover 15 to the pouch 10 comprises resilient members 18 such as shown in Fig. 3. The members 18 are preferably in the form of a stud formed of rubber or similar resilient material and embodying a central body portion 19 having one end thereof provided with an enlarged head portion 20 and having an integral enlarged retaining portion 21 spaced relative to the head portion 20 and further having a reduced extension 23 extending outwardly of the enlarged retaining portion 21.

The pouch 10 and cover 15 are provided near each end of the case with aligned openings 22 (Figs. 4 and 5) of a size to receive the main body portion 19 of the hinge member 18.

The retaining portion 21 is provided with a tapered outer end 21a having the elongated extension 23 thereon whereby, to connect the cover 15 to the pouch 10, the extension 23 can be inserted through the openings 22, preferably from the rear, and can be grasped from the inside of the pouch 10 whereby the retaining portion 21, due to its inherent resiliency, can be pulled through the openings 22 to the final desired position, whereupon the tendency of the material of the retaining portion 21 to return to its initial shape will permit the retaining portion 21 to effi-

ciently act to retain the cover and pouch in assembled relation as described. The head portion 20 and retaining portion 21 of the hinge member 18 are both of larger diameter than the diameter of the openings 22 whereby said portions 20 and 21 will prevent accidental removal of the hinge member 18 from the openings 22. The extension 23 can subsequently be removed as by clipping to permit free and ready access to the interior of the pouch 10.

As shown in Fig. 2, it is desirable to provide one of the hinge members 18 adjacent each end of the case. However, a greater number of the hinge members 18 can be provided if desired.

The main body portion 19 of the hinge member 18 is of a controlled length substantially equal to or slightly shorter than the combined thicknesses of the walls of the cover 15 and pouch 10. Thus the head portion 20 and retaining portion 21 of the hinge member 18 will each be constantly urged toward the adjacent surface of the respective portions of the case and will thus continually urge the cover 15 into closed relation with the pouch 10.

The cover 15 may, however, be manually moved into open relation with respect to the pouch 10 as shown in Fig. 5. In this instance the main body portion 19 of the hinge member 18 will be stretched and caused to elongate against its inherent resiliency and when the cover 15 is released the natural tendency of the body portion 19 to return to its normal shape and size will cause the cover to close.

A modified type of resilient hinge is shown in Figs. 6, 7 and 8 and comprises an elongated strip of elastic thread 24, the end portions of which are inserted through the aligned openings 22 in the cover 15 and pouch 10 of the case. The extreme ends 25 of the thread 24 are knotted or otherwise prevented from withdrawing through the openings 22 and the main portion 26 of the thread 24 is adapted to overlie the outer surface of the cover 15 between the paired openings 22 with the knotted ends 25 of the thread 24 preferably being located on the inner surface of the pouch 10 adjacent the openings 22. Thus the inherent resiliency of the elastic thread 24 will tend to continually urge the cover 15 into closed relation with the pouch 10. Manual force can, however, be applied to open the cover whereupon the elastic thread 24 will be caused to elongate (Fig. 8) and when the cover is released the inherent tendency of the thread to assume its initial shape and size will cause the cover to close.

From the foregoing it will be apparent that all of the objects and advantages of the invention have been accomplished. It will be apparent, however, that many changes may be made in the details of construction, arrangement of parts and method shown and described without departing from the spirit of the invention as expressed in the accompanying claims. Therefore, it is to be understood that all matter set forth or shown in the accompanying drawing is to be interpreted as illustrative and not in a limiting sense.

We claim:

1. A case of the character described comprising a plural-sided pouch having an open mouth, a separate cover for enclosing the open mouth of said pouch, said cover having a top portion and a continuous peripheral flange integral with and angularly extending from said top portion, said cover being shaped to fit over the open mouth of said pouch with said flange overlying the adjacent sides of the pouch, one of said sides of the

5 pouch and portion of the flange overlying said side having a pair of spaced aligned openings, and hinge means connecting said cover to said pouch comprising a stud portion formed of resilient material and extending through said aligned openings in the side of pouch and adjacent overlying portion of the flange of said cover, and retaining means on each end of said stud portion of a diameter greater than the diameter of said aligned openings for preventing dislocation of said stud portion from said openings, one of said retaining means being formed of resilient material and characterized by its ability to compress upon application of strain to an extent whereby it may be drawn through said aligned openings and to subsequently return to its initial size and shape to form abutment means for preventing withdrawal of the stud portion under normal conditions of use, and said stud portion having a normal length between said retaining means equal to about the thickness of said side of the pouch and overlying flange together whereby the hinge means will tend to continually and yieldably urge the cover into closed relation with the mouth of pouch.

2. A case of the character described comprising a plural-sided pouch having an open mouth, a separate cover for enclosing the open mouth of said pouch, said cover having a top portion and a continuous peripheral flange extending angularly from said top portion, said cover being shaped to fit over the open mouth of said pouch with said flange overlying the adjacent sides thereof, one of said sides of the pouch and portion of the flange overlying said side having a pair of spaced aligned openings therein, and hinge means connecting said cover to said pouch comprising an elastic strip having one end thereof extended through one pair of said aligned openings in said pouch and adjacent overlying flange and anchored within said pouch, said strip extending along the outer surface of said flange and having its other end extended through the remaining pair of aligned openings in the pouch and flange and anchored within said pouch whereby said cover will be continually and yieldably urged in the direction of closed relation with said pouch.

3. A spectacle case of the character described comprising a plural-sided pouch of size and shape to seat a pair of spectacles and having an open mouth through which the spectacles may be inserted, a separate cover having a top portion shaped to fit over said open mouth of the pouch and having an angularly disposed continuous peripheral flange to overlie the marginal portion of the sides of the pouch about said mouth, one of the sides of said pouch having a pair of spaced openings in said marginal portion thereof, and the adjacent portion of the flange overlying said marginal portion having apertures therein aligned with said spaced openings, and resilient means extending through said aligned apertures and openings, said resilient means having portions thereof overlying the outwardly related surfaces of the flange and marginal portion of the pouch about the said respective apertures and openings to maintain the cover and pouch in hingedly connected relation, and the intermediate portion of the resilient means between said overlying portions having a normal length not substantially exceeding the thickness of said flange and marginal portion of the cover and pouch together whereby said resilient member will tend to con-

tinually and yieldably urge the cover into closed relation with said mouth of the pouch.

4. A spectacle case of the character described comprising a plural-sided pouch of size and shape to seat a pair of spectacles and having an open mouth through which the spectacles may be inserted, a separate cover having a top portion shaped to fit over said open mouth of the pouch and having an angular disposed continuous peripheral flange to overlie the marginal portion of the sides of the pouch about said mouth, one of the sides of said pouch having a pair of spaced openings in said marginal portion thereof, the adjacent portion of the flange overlying said marginal portion having apertures therein aligned with said spaced openings, and a pair of resilient members having a central body portion extending through said aligned apertures and openings, and terminating in enlarged end portions having a substantially flat surface overlying the outwardly related surfaces of the flange and marginal portion of the pouch about the said respective aperture and opening to maintain the cover and pouch in hingedly connected relation, and said central body portion of the resilient member between said enlarged end portions having a normal length substantially equal to the separation of said outwardly related surfaces when the cover and pouch are in closed relation whereby the resilient member will be stretched temporarily on swinging of the cover to an open position and will on release of the cover function to resiliently urge it to return into closed relation with said mouth of the pouch.

5. A spectacle case of the character described comprising a plural-sided pouch of size and shape to seat a pair of spectacles and having an open mouth through which the spectacles may be inserted, a separate cover having a top portion shaped to fit over said open mouth of the pouch and having an angular disposed continuous peripheral flange to overlie the marginal portion of the sides of the pouch about said mouth, one of the sides of said pouch having a pair of spaced openings in said marginal portion thereof, and the adjacent portion of the flange overlying said marginal portion having apertures therein aligned with said spaced openings, rubber hinge means having a central body portion extending through said aligned apertures and openings, said hinge means having spaced retaining means thereon overlying the opposed outwardly related surfaces of the flange and marginal portion of the pouch about the said respective apertures and openings to maintain the cover and pouch in hingedly connected relation, and the normal length of said central body portion of the re-

silent hinge means between said retaining means thereon not substantially exceeding the separation of said opposed outwardly related surfaces of said flange and marginal portion of the pouch whereby said resilient member will tend to continually and yieldably urge the cover into closed relation with said mouth of the pouch.

6. A spectacle case of the character described comprising a one-piece plural-sided pouch of size and shape to seat a pair of spectacles and having an open mouth through which the spectacles may be inserted, said pouch having an upwardly curving portion in the lower surface dividing the pouch into a pair of pockets, one 15 for each of the lenses of the spectacles to be inserted therein and said upwardly curving portion functioning to support the bridge of said spectacles, a cover having a top portion shaped to fit over said open mouth of the pouch and having 20 a continuous peripheral flange angled downwardly to overlie the marginal portion of the sides of the pouch about said mouth, one of the sides of said pouch having a pair of spaced openings in said marginal portion thereof, and the adjacent portion of the flange overlying said marginal portion having apertures therein aligned with said spaced openings, and resilient hinge means extending through said aligned apertures and openings, said resilient means having portions thereof overlying the outwardly related surfaces of the flange and marginal portion of the pouch about the said respective apertures and openings to maintain the cover and pouch in hingedly connected relation, and the intermediate portion of the resilient member between said overlying portions having a normal length not substantially exceeding the separation of said outwardly related surfaces of said flange and marginal portion of the cover and pouch when 35 in closed relation whereby said resilient means will function to continually and yieldably urge the cover into closed relation with said mouth of the pouch.
